US0D1083783S

(12) **United States Design Patent** (10) Patent No.: **US D1,083,783 S**
(45) Date of Patent: ** Jul. 15, 2025

(54) **BATTERY PACK**

(71) Applicant: **Greenworks (Jiangsu) Co., Ltd**,
Jiangsu (CN)

(72) Inventors: **Song Zhang**, Jiangsu (CN); **Jianlong Chen**, Jiangsu (CN); **Jie Kuang**, Jiangsu (CN); **Jiatao Li**, Jiangsu (CN)

(73) Assignee: **Greenworks (Jiangsu) Co., Ltd**,
Changzhou (CN)

(**) Term: **15 Years**

(21) Appl. No.: **29/924,195**

(22) Filed: **Jan. 17, 2024**

(30) **Foreign Application Priority Data**

Sep. 7, 2023 (CN) 202330581829.5

(51) LOC (15) Cl. **13-02**

(52) U.S. Cl.

USPC **D13/103**; D13/110; D13/107

(57) **CLAIM**

The ornamental design for a battery pack as shown and described.

DESCRIPTION

FIG. 1 is a top, front and left side perspective view of a battery pack showing our new design;

FIG. 2 is a top, rear and right side perspective view thereof;

FIG. 3 is a bottom, front and left side perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof; and,

FIG. 9 is a bottom plan view thereof.

The broken lines in the drawings illustrate portions of the battery pack which form no part of the claimed design.

1 Claim, 9 Drawing Sheets
